US0D1027988S

(12) **United States Design Patent** (10) **Patent No.:** **US D1,027,988 S**
(45) **Date of Patent:** **** May 21, 2024**

(54) **DISPLAY SCREEN OR PORTION THEREOF WITH ICON**

(71) Applicant: **Lutron Technology Company LLC**,
Coopersburg, PA (US)

(72) Inventor: **Jennifer Wong**, Breinigsville, PA (US)

(73) Assignee: **Lutron Technology Company LLC**,
Coopersburg, PA (US)

(**) Term: **15 Years**

(21) Appl. No.: **29/854,830**

(22) Filed: **Sep. 28, 2022**

Related U.S. Application Data

(63) Continuation of application No. 29/809,417, filed on Sep. 28, 2021, now Pat. No. Des. 968,435, which is a continuation of application No. 29/771,646, filed on Feb. 24, 2021, now Pat. No. Des. 934,280, which is a continuation of application No. 29/719,428, filed on Jan. 3, 2020, now Pat. No. Des. 914,725.

(57) **CLAIM**

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with icon showing the claimed design.

The peripheral dashed broken lines illustrate a display screen or portion thereof, and form no part of the claimed design.

1 Claim, 1 Drawing Sheet
(1 of 1 Drawing Sheet(s) Filed in Color)
